UNITED STATES PATENT OFFICE.

ELMER T. WILLHOITE, OF WOODRUFF, MISSOURI.

SCREEN-DOOR CONSTRUCTION.

1,159,144.

Specification of Letters Patent.

Patented Nov. 2, 1915.

Application filed December 15, 1914. Serial No. 877,373.

To all whom it may concern:

Be it known that I, ELMER T. WILLHOITE, a citizen of the United States of America, residing at Woodruff, in the county of Platte and State of Missouri, have invented new and useful Improvements in Screen-Door Construction, of which the following is a specification.

This invention relates to improvements in screen door construction and has particular application to a metal door.

In carrying out the present invention, it is my purpose to provide a screen door wherein the frame will be composed of hollow metal tubing and wherein the wire screen may be readily removed from the frame and replaced when necessary.

It is also my purpose to improve and simplify the general construction of screen doors and to provide a door which will be comparatively light in weight and strong and durable in construction.

With the above and other objects in view, the invention consists in the construction, combination and arrangement of parts hereinafter set forth in and falling within the scope of the claims.

In the accompanying drawing; Figure 1 is a view in front elevation of a screen door constructed in accordance with the present invention. Fig. 2 is a sectional view on the line 2—2 of Fig. 1. Fig. 3 is a fragmentary side elevation of a portion of the door showing the parts on an enlarged scale. Fig. 4 is a fragmentary side elevation of a modified form of door. Fig. 5 is an enlarged longitudinal sectional view on the line 5—5 of Fig. 4. Fig. 6 is a cross sectional view through one of the bars of the door.

Referring now to the drawing in detail, 1 designates a substantially rectangular frame comprising vertical side bars 2, 2 and horizontal top and bottom bars 3, 3 respectively connecting the side bars 2, 2 at the ends of the latter and coacting therewith to form the rectangular frame. The side and end bars of the frame are preferably formed of hollow metal tubing and the meeting ends of the various bars are mitered and securely fastened to one another.

In the present instance, each section of tubing is substantially rectangular in cross section and the bars upon one side of the frame at the inner edges thereof are rabbed as at 4 to form a continuous groove extending around the entire frame.

5 designates the wire screen having the side and end edges thereof seated within the rabbeted portions of the respective bars, and disposed upon the side and end edges of the screen within the rabbeted portions of the bars are clamping strips 6 formed with apertures alining with threaded openings in the inner walls of the rabbeted portion to receive fastening screws 7 whereby the 60 clamping strips will be forced into engagement with the marginal edges of the screen and the latter effectively clamped between such strips and the inner walls of the rabbeted portions 4.

In the present instance, a vertical reinforcing bar 8 is disposed approximately centrally of the frame 1 and has the ends thereof secured to the top and bottom bars 3, 3 respectively of the frame. This reinforcing 70 bar is preferably of a thickness equal to the inner edges of the top and bottom bars and fits within seats 9 cut in such edges, suitable means being provided to effect a rigid connection between the reinforcing bar and the 75 end bars.

A clamping strip 10 is placed in engagement with the surface of the screen 5 opposite from the reinforcing bar 8 and such strip is formed with apertures alining with threaded openings in the reinforcing bar to receive securing screws 11 whereby the strip 10 will be clamped into engagement with the adjacent portion of the screen.

12 designates a transversely disposed brace 90 bar or reinforcing bar disposed at a point slightly below the horizontal center line of the door and formed of two sections 13, 13 disposed at opposite sides of the vertical reinforcing bar 8 and having the inner ends 95 thereof suitably secured to the adjacent edges of the vertical reinforcing bar and the outer extremities disposed within seats formed in the inner edges of the side bars and fastened within such seats. The transverse brace bar 12 is preferably of a thickness equal to that of the inner edges of the longitudinal bars 1 and disposed upon the side of the screen 5 opposite from the transverse brace bar 12 is a securing strip 14 100 formed of sections corresponding to the sections 13 of the brace bar, such sections having apertures formed therein alining with threaded openings in the brace bars to receive securing screws 15 whereby the securing strip may be clamped against the adjacent portion of the screen 5.

In the modified form of the invention illustrated in Figs. 4 and 5, I have shown the end bars 3, 3 and the transverse reinforcing bar 12 as formed of telescopic sections 16, 17, the former being adapted to telescope within the latter. By means of this construction, the width of the door may be varied in accordance with the similar dimension of the door opening. Any suitable means may be employed for holding the telescopic sections 16, 17 in adjusted position. In the present instance, the section 17 carries a set screw 18 designed to bind against the adjacent end portion of the section 16 to hold the parts rigidly connected.

I claim:

In screen door construction, a substantially rectangular frame comprising vertical side bars and horizontal end bars, each formed of hollow metal tubing, said bars at one side of the frame having the inner edges thereof rabbeted to form a continuous groove around the frame, a screen having the marginal edges thereof seated within the groove, a vertical reinforcing bar disposed approximately centrally of said frame and having the extremities thereof secured to said end

bars and disposed upon one side of said screen and formed of hollow metal tubing, a securing strip engaging the screen at the opposite side of said reinforcing bar, means clamping said strip against the screen, a horizontal reinforcing bar composed of tubular metal sections disposed at opposite sides of said vertical reinforcing bar and having the inner ends thereof connected with the respective sides of the vertical reinforcing bar and the outer extremities secured to the inner edges of said vertical side bars, said last-named reinforcing bar being disposed upon one side of the screen, a clamping strip upon the opposite side of the screen and engaging the adjacent portion of the latter and formed of sections corresponding with the sections of said second-named reinforcing bar, and means for securing said strip to said horizontal reinforcing bar.

In testimony whereof I affix my signature in presence of two witnesses.

ELMER T. WILLHOITE.
